ANTI-CROSSING ATTACHMENT FOR SKIS

Douglas L. Grant, 11 Bayview Road,
Marblehead, Mass. 01945

Filed Nov. 14, 1973, Ser. No. 415,822

Term of patent 14 years

Int. Cl. D21—02

U.S. Cl. D34—14 D

FIG. 1

FIG. 2

FIG. 3

FIG. 4

FIG. 5

FIG. 6

FIG. 1 is a perspective view of an anti-crossing attachment for skis, showing my new design;

FIG. 2 is a top plan view thereof;

FIG. 3 is a front elevational view;

FIG. 4 is a left-side elevational view;

FIG. 5 is a right-side elevational view; and,

FIG. 6 is a bottom plan view.

I claim:

The ornamental design for an anti-crossing attachment for skis, as shown.
